ELECTRIC SWITCH

Albert E. Baak, Minneapolis, Minn., assignor to
Minneapolis-Honeywell Regulator Company,
Minneapolis, Minn., a corporation of Delaware

Application March 29, 1940, Serial No. 326,692

8 Claims. (Cl. 200—67)

The present invention relates to electric switches and is concerned more particularly with a switch employing mechanical means to obtain a snap action.

An object of the invention is to provide novel means to obtain a snap action in an electric switch.

Another object is to provide a mechanically operated electric switch in which a single spring is effective both to cause the contacts to be moved with a snap action and to provide a self return of the switch to an initial condition.

Other objects will be apparent from the drawing, specification, and claims.

In the drawing:

Figure 1 is a view of one side of the switch showing the cover in place but in section to disclose the internal mechanism.

Figure 2 is a view of the top of the switch with the cover removed, and

Figure 3 is a view of the side of the switch opposite to the side shown in Figure 1.

Figure 4 is a partial view similar to Figure 2 with certain parts removed.

The switch which is shown in different views in the four figures of the drawing comprises a base 10 moulded of suitable insulating material. On one end of the base and formed integral therewith is an upstanding contact carrying portion 11. Likewise, on the opposite end of the base is a second upstanding contact carrying portion 12. A resilient contact blade 14 extends longitudinally of the switch from the top of the upstanding portion 11 of the base 10 and is secured thereto by a screw 15 which screws into a suitable metal sleeve 17 embedded in the portion 11 of the base and extending vertically therethrough to the bottom of the base 10 where a terminal screw 18 enables an external electrical connection to be made to the contact blade 14.

Likewise, to the upstanding portion 12 at the other end of the base 10 is secured a contact blade 20 by means of a screw 21 which is secured into a metal sleeve 23 embedded in the portion 12 of base 10. Like the sleeve 17 in the other end of the base, this sleeve extends vertically therethrough so that an external electrical connection can be made to blade 20 by means of a terminal screw 24. Contact blade 14 is substantially straight and has mounted on the lefthand end thereof as seen in Figures 2 and 3 a suitable contact button 26 preferably of silver. A similar cooperating contact 27 is mounted on blade 20. The blade 20 has a por-

tion 29 extending beyond contact 27 and bent downwardly to frictionally engage the base 10 for the purpose of damping out any vibration set up in the contact blades as contact 26 is snapped into engagement with contact 27.

I provide a novel snap action mechanism for operating the contacts above described. A support 31 is suitably secured to the base 10 as by rivets (not shown) and is stamped from a single sheet of metal. As best shown in Figure 1, the support includes three pairs of upstanding ear portions 32, 33 and 34 which serve purposes as will be hereinafter pointed out. The right-hand edges of ear portions 33 as shown in Figure 1 are so formed as to provide V-shaped notches 37 which serve to pivot a leaf spring 38 which is provided with a second abutment in the form of a screw 39 which may be adjusted through the bottom of base 10 to vary the tension of the spring 38. The right-hand end of spring 38 as seen in Figure 1 is bent upwardly in the form of a pair of ear portions 41. A contact actuating lever 43 having an opening 44 through its center is pivoted at its right-hand end (Figure 1) in the ear portions 41 extending upwardly from spring 38. The ear portions 41 extend through a pair of slots 47 in actuating lever 43, as best seen in Figure 2. This end of lever 43 is bent upwardly in order to form a knife edge contact with ear portions 41 thereby reducing friction. The opposite end of lever 43 is movable between stops 45 and 46 formed in the upstanding ear portions 32 of the supporting member 31. As best seen in Figure 2 lever 43 has a portion 48 extending under contact blade 14 for separating the contacts when the mechanism is actuated so that the lever 43 is against the upper stop 46.

A link member 50 is pivoted in lever 43 in a knife edge contact in the right-hand end of the opening 44 and extends generally parallel to lever 43 but is adapted to be actuated over center with respect thereto. The opposite end of link 50 is pivoted in a knife edge contact to an operating lever 52 which in turn is pivoted by means of a knife edge contact in the two upstanding ear portions 34 of support 31. The two knife edge portions of the lever 52 are separated by an extension 53 of lever 52 extending between the ear portions 34. It will be noted that by providing two spaced pivots for lever 52 in the two ear portions 34 of support 31 this member is given lateral stability so that the parts will remain in proper lateral alignment. The upstanding portions 33 of support 31 which form

the pivots 37 for spring 38 is also formed to provide stops 54 and 55 to limit movement of the operating lever 52, by engaging a pair of ears 52' extending laterally from the lever 52 as best seen in Figure 4.

It will be noted in Figure 4 that the contact actuating lever 43 and the leaf spring 38 including the upstanding ear portions 41 have been removed to show more clearly the operating lever 52 and the ears 52' thereon in their relation to the ear portions 33 and 34 which extend upwardly from the support 31.

The upper stops 54 of the ear portions 33 of the support 31 serve to prevent clockwise movement of operating lever 52 to a point much 15 beyond the position of lever 52 at which the snap action occurs which closes the contacts. These stops therefore maintain a predetermined tension on the spring 38 and serve to hold the various parts in their proper position when there 20 is no force applied to the lever 52 tending to move it in a counter-clockwise direction as shown in Figure 1.

A cover 57, preferably of insulating material, is shown in Figure 1 and is provided with an aperture 58 in the top thereof through which a push button 60 extends. A lower portion 61 of push button 60 engages the operating lever 52 at a point between the two pairs of stops 54 and 55.

The operation of my switch is as follows: with the various parts of the switch in the position shown in the drawing, an initial tension exists in the spring 38. This tension is adjustable by means of the screw 39 to bow the spring 38 so that it takes a slight downward curve in the middle. The upstanding ear portions 41 of spring 38 are therefore exerting a force on contact actuating lever 43 tending to move it to the right as seen in Figure 1. Such movement is prevented by the operating lever 52 and the link 50. Counter-clockwise rotation of actuating lever 43 is prevented by the stops 46 in the ear portions 33 while endwise movement is prevented by the link 50. The link 50 is prevented from moving endwise by the operating lever 52 which abuts the ears 34 at its pivot therein and is prevented from rotating clockwise (as in Figure 1) by the stops 54 in the ears 33. If no downward force is applied to the operating lever 52, it will assume its uppermost position because the stops 55 in the ears 33 prevent alignment of the pivots of the link 50 and the lever 52. Since these pivots are never aligned, the spring 38 biasing the actuating lever 43 to the right will continually tend to collapse the toggle joint formed by the link 50 and the operating lever 52. Thus the link 50 will be pivoted in the lever 52 at a point above the actuating lever 43 and will consequently bias the lever 43 against the lower pair of stops 45. The stops 46 and 55 and the pivot of the lever 52 in the ears 34 are so disposed that the lever 52 is also biased upwardly by the spring 38 when the lever 52 is in its lowermost position. Hence when no external force is applied to the switch, the parts will always be in the position shown.

When a downward force is applied to push button 60, operating lever 52 is caused to rotate counter-clockwise about its pivot in the ear portions 34. When the pivot of the lever 52 in the link 50 becomes aligned with the pivots at the two ends of contact actuating lever 43, a dead center condition will exist. Further movement of lever 52 in a counter-clockwise

direction will therefore cause the left-hand end of the contact actuating lever 43 as seen in Figure 1 to snap upwardly to open the contacts 26 and 27. It is not necessary that lever 52 be moved further in a counter-clockwise direction once this snap action is instigated because the spring 38 biasing contact actuating lever 43 longitudinally will supply the energy for the clockwise snap of lever 43 from the lower stop 45 to the upper stop 46. The lower stop 55 in ear portions 33 of support 31 is effective therefore to prevent excessive counter-clockwise movement of the lever 52 by the push button 60 and prevent alignment of the pivot points of the toggle joint formed by lever 52 and link 50. Because these pivots never become aligned, spring 38 will always be supplying the force tending to collapse the toggle joint formed by lever 52 and link 50. Therefore when the downward force on push button 60 is removed the above mentioned toggle joint will collapse which will raise the pivot between lever 52 and link 50 until it again becomes aligned with the pivots at the two opposite ends of the contact actuating lever 43. When this occurs the left-hand end of lever 43 which has been in contact with the upper stop 46 of the upstanding ear portion 32 of support 31 will move downwardly with a snap action to again close the contacts.

It will therefore be seen that the spring 38 serves to cause operation of the contact actuating lever 43 between stops 45 and 46 with a snap action as is customary in overcenter snap switches. However, by reason of the pivot for the lever 52 in ear portions 34 being out of line with the other pivots of the mechanism during all phases of operation, spring 38 is also able to supply the force necessary to return the mechanism to its initial position. In tracing the action of the spring through the various operations it will be seen that its tension is increased when push button 60 is depressed until the snap action occurs which opens the contacts. During this snap action spring 38 gives up a small amount of its tension to open the contacts. As push button 60 is raised the spring tension decreases until the snap action occurs which opens the contacts. Then during this snap action the spring tension is reduced to its lowest or initial value.

It will therefore be seen that I have provided a novel snap acting electrical switch in which a single spring serves both to cause the snap action and to return the mechanism to its initial position. While one form of the invention has been illustrated and described it is evident that numerous modifications could be made without departing from the spirit of the invention and therefore I wish to be limited only by the appended claims.

I claim as my invention:

1. In an electrical switching mechanism, in combination, a support, a pivoted contact actuating lever, a pair of stops for limiting rotational movement of said lever, a toggle joint having a first rigid link pivoted in said lever and a second rigid link pivoted in said support, a spring carried by said support and acting on said lever tending to collapse said toggle joint, and a stop limiting the amount of collapse of said toggle joint, the pivot for said second link in said support being located out of line with respect to the pivots for said contact actuating lever and for said first link in said actuating lever so that as said toggle is moved toward

aligned position, the center pivot of the toggle will be moved over center with respect to the pivot for said lever and the pivot for said toggle joint in said lever without alignment of the pivot points of the toggle joint.

2. In an electrical switching mechanism, in combination, a support, a pair of mating contacts, an actuating member pivoted with respect to said support for moving one of the contacts, means carried by said support to limit rotational movement of the actuating member about its pivot, a toggle joint pivoted at one end in the actuating member and pivoted at the other end in said support at a point so located that the center pivot of the toggle can pass over center with respect to the pivot for the actuating member and the pivot of the toggle joint in the actuating member without the pivots of the toggle joint becoming aligned, and a spring acting on the pivot for said actuating member to place the two links of the toggle joint in compression.

3. In an electrical switching mechanism, in combination, a leaf spring, a pivot carried by said spring, a pair of abutments for said spring, a contact actuating lever carried in the pivot that is carried by said spring, a pair of stops for limiting movement of said contact actuating lever about its pivot, a link pivoted in said lever to oppose by compression the force of said spring on said contact actuating lever, a second pivot for said link movable over center with respect to the pivots in said contact actuating lever, a second lever pivoted at one end in said second pivot for said link and at the other end at a point out of line with the dead center of said mechanism, and means for actuating said second lever.

4. In an electrical switching mechanism, in combination, a support, a pivoted contact actuating lever, a pair of stops for limiting rotational movement of said lever, a toggle joint having a first rigid link pivoted in said lever and a second rigid link pivoted in said support, a spring carried by said support and acting on said lever tending to collapse said toggle joint, a stop limiting the amount of collapse of said toggle joint, the pivot for said second link in said support being located out of line with respect to the pivots for said contact actuating lever and for said first link in said actuating lever so that as said toggle is moved toward aligned position, the center pivot of the toggle will be moved over center with respect to the pivot for said lever and the pivot for said toggle joint in said lever without alignment of the pivot points of the toggle joint, and means associated with said support for adjusting the force of said spring.

5. In an electrical switching mechanism, in combination, a support, a pivoted contact actuating lever, a pair of stops for limiting rotational movement of said lever, a toggle joint

having a first rigid link pivoted in said lever and a second rigid link pivoted in said support, and a spring carried by said support and acting on said lever tending to collapse said toggle joint, the pivot for said second link in said support being located out of line with respect to the pivots for said contact actuating lever and for said first link in said actuating lever so that as said toggle is moved toward aligned position, the center pivot of the toggle will be moved over center with respect to the pivot for said lever and the pivot for said toggle joint in said lever without alignment of the pivot points of the toggle joint.

6. In an electrical switching mechanism, in combination, a support, a contact actuating lever resiliently pivoted in said support so as to be biased longitudinally with respect thereto, means for limiting rotational movement of said actuating lever with respect to said support, a toggle joint having a first rigid link pivoted in said lever and a second rigid link pivoted in said support, the axis of the pivot for said toggle joint in said support lying outside a plane passed through the axes of the pivots of said actuating lever in said support and of said toggle joint in said actuating lever at all positions of said actuating lever.

7. In an electrical switching mechanism, in combination, a support, a contact actuating lever, a pivot for said actuating lever carried by said support, means for limiting rotational movement of said actuating lever with respect to said support, a toggle joint having a first rigid link pivoted in said lever and a second rigid link pivoted with respect to said support, a pivot for said second link carried by said support, the axis of said pivot for said toggle joint lying outside a plane passed through the axes of said pivot for said actuating lever and the pivot for said toggle joint in said lever at all positions of said actuating lever, and spring means carried by said support and acting on one of said pivots for placing said actuating lever in tension.

8. In an electrical switching mechanism, in combination, a support, a contact actuating lever, a pivot for said actuating lever carried by said support, means for limiting rotational movement of said actuating lever with respect to said support, a toggle joint having a first rigid link pivoted in said lever and a second rigid link pivoted with respect to said support, a pivot for said second link carried by said support, the axis of said pivot for said toggle joint lying outside a plane passed through the axes of said pivot for said actuating lever and the pivot for said toggle joint in said lever at all positions of said actuating lever, spring means carried by said support and acting on one of said pivots for placing said actuating lever in tension, and means associated with said support for adjusting the force of said spring means.

ALBERT E. BAAK.
